UNITED STATES PATENT OFFICE.

GEORGE E. BRYSON, OF OMAHA, NEBRASKA.

SIFTING-GRAVE.

1,359,869.

Specification of Letters Patent. Patented Nov. 23, 1920.

Application filed April 24, 1918. Serial No. 230,478.

To all whom it may concern:

Be it known that I, GEORGE E. BRYSON, a citizen of the United States, residing at Omaha, in the county of Douglas, State of Nebraska, have invented certain new and useful Improvements in Sifting-Grates; and I do hereby declare the following to be a full, clear, and exact description of the invention, such as will enable others skilled in the art to which it appertains to make and use the same.

This invention relates to ash and coal sifters and has special reference to novel attachments for stoves and furnaces, in the form of a sifting grate.

One important object of the invention is to provide an improved general construction of devices of this character.

A second important object of the invention is to provide an improved form of sifting grate which may be positioned in a stove or furnace beneath the regular grate and which will catch the coal and ashes dropping from the regular grate, the device being arranged to separate the fine ashes or powder from the unburned coal by manual operation.

A third important object of this invention is to provide a device of this character which may be removed bodily from the stove or furnace when loaded with unburned coal so that the latter may be dumped back in the coal pile or bin, or other desired place.

With the above and other objects in view, as will be hereinafter apparent the invention consists in general of certain novel details of construction and combinations of parts hereinafter fully described, illustrated in the accompanying drawing and specifically claimed.

In the accompanying drawing, like characters of reference indicate like parts in the several views, and:—

Figure 1 is a perspective view of the device.

Fig. 2 is a transverse section thereof.

Fig. 3 is a longitudinal section thereof.

Fig. 4 is a view of one corner of the device showing the modified form of end and side wall.

In the form of the invention herein illustrated there is disclosed a top frame 10 and a bottom frame 11. These frames are held in spaced relation by suitable uprights 12

and carried by said frames are the side members 13 and end members 14, both the latter being preferably formed of wire netting as shown in Figs. 1 to 3 or of perforated sheet metal as shown in Fig. 4.

Extending across the bottom are transverse bars 15 provided with spaced perforations 15^a, the perforations in the several bars standing in a single plane and being alined. Extending longitudinally of the bottom are spaced rods 16 which are securely connected to the transverse bars 15 as by passing through alternate perforations or openings 15^a. Also extending longitudinally of said bottom between, in the plane of, and alternating with the rods 16 are other rods 17 which pass through the remaining perforations 15^a and through alined perforations in the front end of this device, being there united to a cross bar 18 provided with an operating handle 19. Furthermore these rods 17 have upwardly projecting spaced fingers 20 which are so arranged that they not only constitute agitators for the mass of coal and ashes which drop in the receptacle, but also, through their engagement with one of the bars 15, limit the forward movement of the rods 17, while the rear ends of the latter engage the rear bar of the frame 11 to limit their rearward movement.

It is to be noted that the rear cross bar 15 is spaced from the rear end of the device and that, when the rods 17 are moved forward, their ends project behind this rear bar. In order to prevent ashes from dropping down in this space there is provided a reticulated screen or guard 21 which is secured to the upper rear edge of the body of the device and has its lower edge secured to the bar 15 at the rear. Thus the space is protected so that when the rods 17 are drawn forward the ashes and coal will not drop through this space.

Moreover it is found convenient to provide the device with a handle 22 so that it may be withdrawn from the stove or furnace when desired.

It will be obvious that in order to support the device just beneath the regular grate of the stove or furnace, suitable means are employed in the ash pit of the furnace or stove. These means may take the form of lugs on the side walls of the ash pit or the device

may rest directly on top of the removable ash pan. However, the specific means for supporting the device does not constitute any part of the invention and it is not deemed necessary here to show the same.

In operation the device is placed below the grate of the furnace and the stove manipulated in the usual manner. By reason of the sifter having an open top any 10 ashes and fine coal which may fall through the regular grate will drop into the device and be caught by the rods 16 and 17. By grasping the handle 19 and reciprocating the rods 17 the fingers 20 will agitate the 15 mass on the sub-grate thus formed and the powdered ashes will sift through while the fine coal will remain on top. When sufficient fine coal has been collected on top of the rods then the handle 22 may be grasped 20 and the entire device withdrawn from the stove or furnace and dumped in any convenient place.

There has thus been provided a simple and efficient device of the kind described and 25 for the purpose specified.

Having thus described the invention, what is claimed as new, is:

In a sifting grate, the combination with a frame, sides and ends rising therefrom, and cross bars within the frame having 30 alined perforations standing in a single plane; of a series of rods slidably mounted through alternate perforations and extending through the front of the frame and connected by a handle, a second series of rods 35 fixed through the remaining perforations and spaced from the first series to permit the passage of dust; a reticulated guard inclined from the upper edge of the rear end of the frame to the rear cross bar, and agitating fingers rising from the slidable rods, the foremost fingers striking the front of the frame before the rear ends of said rods are drawn from beneath the guard.

In testimony whereof I affix my signature 45 in the presence of two witnesses.

GEORGE E. BRYSON.
